US00D457037S

(12) **United States Design Patent** (10) Patent No.: **US D457,037 S**
 Hayes (45) Date of Patent: **** May 14, 2002**

(54) **BOWL**(75) Inventor: **Thomas J. Hayes**, McHenry, IL (US)(73) Assignee: **Pactiv Corporation**, Lake Forest, IL (US)(**) Term: **14 Years**(21) Appl. No.: **29/138,914**(22) Filed: **Mar. 21, 2001**(51) LOC (7) Cl. .... **07-01**(52) U.S. Cl. .... **D7/584; D7/543; D7/586**(58) Field of Search ..... **D7/584, 586, 585, D7/558, 540, 611, 608, 503, 602, 601, 500, 538, 565, 546, 545, 543, 542, 555; 220/23.8, 574, 4.21, 260, 669, 787, 710.5; D9/429; 206/508; 229/406**(56) **References Cited**

(57) **CLAIM**

The ornamental design for a bowl, as shown.

DESCRIPTION

FIG. 1 is a perspective view of a bowl;

FIG. 2 is a side view of a bowl;

FIG. 3 is a bottom view of a bowl; and,

FIG. 4 is a top view of a bowl.

1 Claim, 4 Drawing Sheets
